US0D1012126S

(12) **United States Design Patent** (10) Patent No.: US D1,012,126 S
Anthony et al. (45) Date of Patent: ** Jan. 23, 2024

(54) **DISPLAY SCREEN WITH AN ICON**

(71) Applicant: **JuvYou Limited**, Douglas (IM)

(72) Inventors: **Joshua Christian Anthony**, Princeton Junction, NJ (US); **Justin Max**, Pipersville, PA (US); **Matthew Flick**, Brevard, NC (US); **Amy Sacchetta**, Chalfont, PA (US)

(73) Assignee: **JUVYOU (EUROPE) LIMITED**, Dublin (IE)

(**) Term: **15 Years**

(21) Appl. No.: **29/830,378**

(22) Filed: **Mar. 11, 2022**

(51) **LOC (14) Cl.** **14-0**

(52) **U.S. Cl.** **D14/483**
